UNITED STATES PATENT OFFICE.

JAMES A. DILLON, OF CHICAGO, ILLINOIS.

WATER-HEATER.

1,073,222.

Specification of Letters Patent. Patented Sept. 16, 1913.

Original application filed March 27, 1912, Serial No. 617,247. Divided and this application filed November 22, 1912. Serial No. 732,826.

To all whom it may concern:

Be it known that I, JAMES A. DILLON, a citizen of the United States, residing in Chicago, in the county of Cook and State 5 of Illinois, have invented a new and useful Improvement in Water-Heaters, of which the following is a specification.

This invention relates to improvements in water heaters, and more particularly to that 10 type of water heaters employed in laundries to supply quantities of heated water to the washing machines, and is a division of my pending application, Serial No. 617,247, filed March 27, 1912.

15 An object of the invention is to provide a water heater of the type above indicated, which is adapted to supply large quantities of hot water to washing machines in laundries, and which will utilize exhaust steam 20 without additional expense for heating to the laundries.

Another object of the invention is to provide a water heater or condenser that will rapidly condense the exhaust steam and heat 25 the water, and which is provided with means for separating oil from the steam as the same passes through the heater or condenser.

Other objects of the invention are to provide means which will insure the utilization 30 of all the latent heat of the steam and means in the form of a steam condenser located within the storage tank for the hot water, said last named means serving to heat the water to a higher temperature than would 35 otherwise be possible.

In the drawing forming a part of this specification, Figure 1 illustrates a mechanism embodying my improvements, parts being broken away to more clearly illustrate 40 the construction and to prevent crowding. Fig. 2 is a vertical, sectional view, upon a somewhat enlarged scale, of the main heater or condenser, and Fig. 3 is a detail view, showing the arrangement of certain of the 45 pipes within the heater or condenser shown in Fig. 2.

In said drawing, exhaust steam is adapted to be supplied from the exhaust port of a steam engine (not shown) through the pipe 50 10, and is then superheated by means of a coil 11, preferably placed in the stack (not shown) of the furnace to thereby employ heat which would otherwise be wasted. The superheated steam next enters the main 55 heater or condenser, designated generally by

the reference 12. The heater or condenser 12, as shown, comprises a large outer cylinder or drum 13, having a bottom 14, a top 15 and an intermediate partition 16 dividing the drum or cylinder into what may 60 be termed, for convenience, a lower primary condensing chamber 17 and an upper, secondary condensing chamber 18. Secured to the upper end 15 of the heater and depending within the upper secondary chamber 18 65 is a water jet cylinder 19, the latter having a bottom plate 20 located preferably near the longitudinal center of the cylinder. The water jet cylinder is closed on the top thereof by means of a cover 21, through which 70 extends a pipe 22 suitably packed by packing material 23 and held in position by nut 24, as shown in Fig. 2, said pipe 22 serving as an outlet for any uncondensed steam in the heater 12. Also extending through 75 the cover 21 is a cold water inlet 25, which extends to a point adjacent the bottom plate 20 and below the level of a double series of circumferentially arranged small perforations 26 formed in the water jet cylinder 19. 80 The superheated exhaust steam enters the lower primary condensing chamber 17 through the pipe 27, which is so arranged that it directs the steam against the wall 13 and causes the steam to have a rotary 85 motion within the chamber, so that any oil which may be carried by the steam will strike against the wall and drain down the same onto the bottom plate 14, and then be drawn off through the drip pipe 28. The 90 exhaust steam by coming in contact with the walls of the lower chamber and the partition 16 will be partly condensed and cooled and will then pass up into the upper chamber 18 through a short vertical pipe 29 which 95 has secured thereto, at the top, a T fitting 30, from which lead in opposite directions horizontal pipes 31, each having a vertical portion 32, the latter at their upper ends being provided with short pipe sections 33 100 which, as shown in Fig. 3, are arranged oppositely so as to direct the exhaust steam against the walls of the upper chamber and cause the steam to have a rapid rotary or whirling motion within the upper chamber 105 and around the exterior of the water jet cylinder 19. The water, as it enters the water jet cylinder through the pipe 25, will be forced out of the water jet cylinder through the perforations 26 in radial 110

streams and into the rapidly rotating steam, thereby condensing the latter and at the same time heating the water, which will fall to the bottom of the chamber 18 and then pass out through the pipe 34 near the bottom of the chamber.

The water jet cylinder is also provided with an additional set of circumferentially arranged perforations 35, larger than the 10 perforations 26 and located above the latter, said perforations 35 being adapted to permit the entrance of steam into the water jet cylinder 19 to maintain sufficient pressure on the water within the water jet cylinder to force the same outwardly in streams, 15 said perforations 35 also allowing water to escape therethrough when water is being admitted to the cylinder at a greater rate than the water flows out through the 20 smaller perforations 26.

The heated water, after passing through the outlet pipe 34, is conducted to a storage tank 36, as shown in Fig. 1 and by reference to Fig. 2, it will be seen that the pipe 22 is extended to a point below the floor plate 20 of the water jet cylinder, and is connected by means of pipe 37 to a coil 38, located in the bottom of the tank 36, said coil 38 being provided with a vertical end 25 pipe 39 leading to the atmosphere and having at its lower end a small drain pipe 40. The heated water is adapted to be drawn from the storage tank 36 by means of pipe 41, having a regulating valve 42 therein, 30 said pipe 41 leading to the washing machines (not shown). The cold water for the water jet cylinder is supplied through a water main 43, having a valve 44 therein controlled by means of lever 45, having a 35 float 46 in the tank 36 operated by the stored water.

A vent pipe 47 is attached to the elbow 48 in the outlet pipe 41, the vent pipe 47 extending up to a point above the normal water level in the tank 36. This vent pipe 45 47 is utilized to prevent any sediment from being sucked up from the bottom of the tank when water is being drawn off through the pipe 41 whenever the water in the tank 50 36 reaches a low level.

The operation of the apparatus is as follows:—The superheated exhaust steam after entering the lower chamber 17 of the heater 12 will be given a rapid rotary movement 55 thereby insuring the depositing of any oil or other foreign matter which may be carried by the steam on the walls of the chamber and after the steam has completed several revolutions within the chamber 17, it 60 will next pass up into the chamber 18 where it will again be given a rapid, rotary motion and will have projected thereinto the radial streams of water coming through the perforations 26. If the tank 36 is not filled 65 with hot water the valve 44 in the water

supply main will thereby be opened and the water will continue to flow into the water jet cylinder and condense the steam which will be drawn off into the tank 36. When the storage tank 36 is full or when an insufficient amount of water is being supplied to the water jet cylinder to condense all the steam, any uncondensed portion thereof will then pass up through the pipe 22 and through the coil 38, whereupon the complete 70 condensation of the steam will be effected, thereby raising the temperature of the stored water still further, and preventing loss of any of the latent heat of the steam. Such condensed steam in the coil 38 may 75 then be drawn off through the drain pipe 40.

Another important result obtained by my arrangement results from the fact that the wall of the secondary condensing chamber 18 is directly exposed to the atmosphere, and hence when the supply of exhaust steam is cut off, the wall will contract so rapidly 80 that it will crack and break off any scale or deposits which may be on the inner side of the walls, resulting from water jets striking thereagainst, and I have found from actual practice that this sudden contraction results in the heater or condenser being practically self-cleaning, as the scale, as fast as broken off, will be washed away through 85 the outlet pipe 34.

Although I have herein shown and described what I now consider to be the preferable form of my improvements, yet I am aware that various changes and modifications may be made in the details of construction and arrangement of parts without departing from the spirit of the invention, and all such changes and modifications are contemplated as fall within the scope of 100 the claims appended hereto.

I claim:—

1. In a water heater, in combination: a shell having a primary and a secondary condensing chamber therein; a water-jet vessel within said secondary chamber, said vessel having a series of apertures therein through which water is adapted to be projected outwardly in radial streams into said secondary chamber; an exhaust steam inlet into the primary chamber; a pipe for conducting the steam from the primary to the secondary chamber, the open end of said pipe within the secondary chamber terminating adjacent to some of said apertures in the water-jet vessel and arranged to give the steam as it enters the secondary chamber a rotary motion around the water-jet vessel, whereby the streams of water are projected into the incoming steam radially; a water supply pipe for said water-jet vessel; and an outlet from said secondary condensing chamber for the condensed steam and heated water, substantially as specified.

2. In a water heater, in combination: an

- outer cylinder having a lower primary and an upper secondary condensing chamber; a water-jet cylinder depending within said secondary chamber, said water-jet cylinder having a plurality of peripheral apertures therein through which water is adapted to be projected outwardly in radial streams; an exhaust steam inlet into said primary chamber; a water supply pipe for said water-jet cylinder; an outlet pipe from said secondary chamber for the condensed steam and heated water; and means for conducting the steam from the primary to the secondary chamber, said means including a plurality of pipes having their upper inlet ends within the secondary chamber arranged to project the steam horizontally thereinto, said horizontal ends of the pipes being located adjacent the apertures in the water-jet cylinder whereby the steam as it enters said secondary chamber is given a rotary motion around the water-jet cylinder and the water is projected thereinto in radial streams, substantially as specified.
3. A water heater of the character described comprising, in combination: a main heater having a condensing chamber; a water-jet cylinder located within said chamber; means for spraying water into steam as it enters said chamber; a combined subsidiary heater and hot water storage tank, said tank having a heating coil therein; a pipe for conducting the heated water and condensed steam from said condensing chamber to the combined heater and storage tank; a pipe connected to one end of said heating coil and opening into the interior of said condensing chamber; and means for admitting exhaust steam to said condensing chamber, substantially as specified.
4. In a water heater, in combination: a main condenser having upper and lower separated condensing chambers therein; a water-jet cylinder disposed within the upper chamber and provided with means for projecting water into the upper chamber in radial streams; a water supply pipe for said water-jet cylinder; pipes for conducting steam from the lower to the upper chamber, said pipes having two separated terminals in the upper chamber arranged to give the steam a rotary motion around the water-jet cylinder and having only a single terminal within the lower chamber; an exhaust steam inlet into the lower chamber; a subsidiary condenser and storage tank having a bank of pipe therein, one end of said bank of pipe being in communication with said upper chamber of the main condenser; and a pipe for conducting the condensed steam and heated water from said upper chamber to the combined subsidiary condenser and storage tank, substantially as specified.
